United States Patent Office

Des. 223,080
Patented Mar. 7, 1972

223,080

BUCKLE

Norman A. Roy, Cold Spring Harbor, N.Y., assignor to
NAR Enterprises, Inc., New York, N.Y.

Filed Aug. 17, 1970, Ser. No. 24,508

Term of patent 14 years

Int. Cl. D2—07

U.S. Cl. D2—446

FIG. 1

FIG. 2

FIG. 4

FIG. 3

FIG. 5

FIG. 6

FIG. 1 is a front perspective view of a buckle showing my new design;

FIG. 2 is a front elevational view thereof;

FIG. 3 is a rear elevational view;

FIG. 4 is a side elevational view as seen from the right of FIG. 2;

FIG. 5 is a bottom plan view; and

FIG. 6 is a front elevational view of a second embodiment of the design.

I claim:

The ornamental design for a buckle, as shown and described.
